UNITED STATES PATENT OFFICE.

HENRY A. STUART, OF NEW YORK, N. Y.

LOCK FOR GAS-KEYS.

SPECIFICATION forming part of Letters Patent No. 633,400, dated September 19, 1899.

Application filed June 28, 1899. Serial No. 722,180. (No model.)

To all whom it may concern:

Be it known that I, HENRY A. STUART, of the city of New York, borough of Brooklyn, in the county of Kings and State of New York, have 5 invented a new and Improved Lock for Gas-Keys, of which the following is a full, clear, and exact description.

My invention relates to an improvement in devices for automatically locking gas-keys 10 so that they cannot be accidentally turned, so as to allow the gas to flow.

My invention comprises the novel features hereinafter described and claimed.

Reference is to be had to the accompanying 15 drawings, forming a part of this specification, in which similar characters of reference indicate corresponding parts in all the figures.

Figure 1 is a side elevation of my invention applied to a gas-key. Fig. 2 is a sectionalelevation taken upon the line 2 2 of Fig. 1. Fig. 20 3 is a partial side elevation of a gas-cock, showing the key turned so as to permit the passage of gas; and Figs. 4 and 5 are perspective views showing two slightly-differing forms of 25 my device detached from the key.

Although my device will be herein described as applied to gas-keys, it is evident that it may be applied to any kind of a plug, cock, or valve, whether used for controlling gas or 30 other fluids.

In Fig. 1 is shown an ordinary gas-fixture containing the key or cock by which the flow of gas is controlled. The casing A is adapted to receive a valve B, said valve being provided with a flattened key B', by means of 35 which it is readily engaged to turn the valve. The casing is also provided with two shoulders C, one of said shoulders being shown in the drawings formed by a flange which extends substantially one-half of the distance about the plug. The parts so far described are all of the usual construction.

Instead of the pin which is ordinarily placed in the stem of the key and which engages the 45 shoulders C to prevent overturning of the valve I employ a spring-wire D, which is constructed after the manner illustrated in Fig. 4. One end of this wire (or that end which is 50 numbered 1) is inserted within the hole ordinarily occupied by the stop-pin. The wire is then bent downwardly and upwardly, forming a loop 2, which lies alongside of the key. The

outer arm of this loop extends upwardly and bears against the side of the plug B at a point opposite where the end 1 is attached to said 55 plug. The wire from thence extends downwardly alongside of the key, forming an arm 4, the lower end of which is bent in the form of a loop or finger-piece 5, by which it may be engaged to pull downward the free end of the 60 loop. The upper or free end of the loop 3 bears against the plug at a point opposite the end 1 and is adapted to engage one of the shoulders C upon the casing A. While the end 1 engages one of these shoulders and prevents 65 overturning of the valve the end 3 engages the other shoulder and prevents the valve from being opened by accidental contact with any object. It cannot be opened until the end 3 has been pulled downward, so as to free 70 it from the shoulder C. This may be done by engaging the finger-piece 5 and exerting a slight downward pressure thereon, which may be easily done at the same time the key is engaged to turn it. By the use of this 75 device gas-keys will be rendered entirely safe and prevent any possibility of their becoming accidentally opened, and thus allow gas to escape. The locking is done automatically, as when the cock is closed in the ordinary 80 manner by turning the key B the end of the loop 3 engages one of the shoulders C.

A slight variation in form of my device is shown in Fig. 5. It is the same as that shown in Fig. 4, with the exception that a coil 6 is 85 formed at the lower end of the loop 2, giving the device a little more spring.

It is evident that the exact shape of this device may be varied. The essential point thereof is the spring-held arm terminating at 90 3 and adapted to engage one of the shoulders C at the same time that the stop-pin or its substitute engages the other shoulder and the finger-piece 5 attached, by which it may be readily engaged to free the key.

Having thus fully described my invention, I claim as new and desire to secure by Letters Patent—

1. A lock for gas-keys and similar cocks, comprising a valve-casing having stops or 100 shoulders upon opposite sides, a plug valve or key fitting said casing, and a spring having one end entering a hole in the plug or key and having its other end yieldingly bearing

against the opposite side of the cock, the two ends being adapted to engage opposite shoulders upon the casing to hold the key closed, substantially as described.

5 2. A lock for gas-keys, comprising a spring-wire having one end entering the key and serving as a stop, said spring extending downward and then upward in a loop, said loop being adapted to bear upon the key opposite the point of attachment of the wire to the key, substantially as described.

3. A lock for gas-keys, comprising a spring-wire having one end entering the key and serving as a stop, said spring extending downward and then upward in a loop, said loop being adapted to bear upon the key opposite the point of attachment of the wire to the key, and a handle or finger-piece secured to said spring-wire, whereby its free end may be freed

from the shoulder of the key, substantially 20 as described.

4. A lock for gas-keys, comprising a spring-wire having one end adapted to enter the key-stem to form a stop-pin, the wire extending thence downwardly and then upwardly forming 25 a loop alongside the key, the upper portion thereof being adapted to engage the shoulders or stops on the valve-casing, the wire thence extending downwardly and at its lower end being provided with a finger-piece 30 or handle by which the free portion thereof may be disengaged from its stop, substantially as described.

HENRY A. STUART.
